(57) **CLAIM**

We claim the ornamental design for a locking slider spring clip assembly, as shown and described.

DESCRIPTION

FIG. 1 is a front perspective view of a locking slider spring clip assembly showing our new design;

FIG. 2 is an exploded perspective view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is rear elevational view thereof;

FIG. 8 is a front perspective view thereof, with locking slider in an unlocked orientation and the spring clip open;

FIG. 9 is a right elevational view thereof;

FIG. 10 is a bottom perspective view thereof; and,

FIG. 11 is a rear perspective view thereof.
